UNITED STATES PATENT OFFICE.

WILLIAM MILTON BROWN, OF JOHNSTOWN, PENNSYLVANIA.

SWITCH-OPERATING MECHANISM.

1,399,540.

Specification of Letters Patent.

Patented Dec. 6, 1921.

Application filed September 29, 1921. Serial No. 504,184.

To all whom it may concern:

Be it known that I, WILLIAM MILTON BROWN, a citizen of the United States, and resident of Johnstown, in the county of Cambria and State of Pennsylvania, have invented certain new and useful Improvements in Switch-Operating Mechanisms, of which the following is a specification.

This invention relates to switch stands and more particularly to means for preventing the breaking or damaging of any of the essential operating parts of the stand when the switch controlled by the stand is trailed.

The invention consists broadly in providing a weakened minor connecting member that will be strong enough to withstand the strains produced in the usual operation of the switch stand and of less strength than any other connection in the train of mechanism so that it will break and allow the free movement of the parts when the switch is trailed.

One of the main objects is to provide a connection of this character that will be inexpensive to manufacture and one that may readily be replaced by a person unskilled in the art.

A further object is to provide a connection of this character that may be used a second time before it need be discarded.

The above and various other objects and advantages will be brought out in the following specification and illustrated in the accompanying drawings, in which:

Figure 1 is a side elevation of a switch stand embodying my invention.

Fig. 2 is a top plan thereof.

Fig. 3 is a detail side elevation of a portion of a switch stand showing a modification of the invention.

Fig. 4 is a bottom plan of the structure shown in Fig. 3.

Referring particularly to the drawings, 2 designates the usual switch stand casing in which is journaled the target shaft 3 having a target 4 on its upper end. The target shaft 3 has a bevel gear 5 secured thereon intermediate its ends, which is in mesh with a bevel gear 6 secured on one end of an operating shaft 7 which extends at right angles to the shaft 3 and is journaled in suitable bearings in the casing 2. A counterweighted hand operated arm or lever 8 is mounted on the free end or end of the shaft 7 which projects

through the casing 2, and the lever 8 is free to rotate thereon.

The lower end of the target shaft 3 is provided with an offset head 9 having a screw threaded aperture therein for the reception of a screw threaded crank arm 10, which has a pivotal connection with one end of the switch rod link 11. The other end of the link 11 is connected to the usual switch rod.

A collar 12 is secured on the free end of the shaft 7 beyond the lever 8 by a pin or bolt 13. A pair of comparatively thin lugs 14 project from the periphery of the collar 12. The lugs 14 are arranged side by side and are of such length that they will project between a pair of ears 15 formed on the operating lever 8 adjacently mounted on the shaft 7. The ears 15 are of materially greater thickness and strength than the lugs 14 and are of such size that only the lug nearest the lever is engaged between them.

It will be readily apparent that when one of the lugs 14 is engaged between the ears 15, the lever 8 will have a positive engagement with the shaft 7.

The usual locking mechanism 16 is provided at each side of the switch stand casing for locking the lever 8 in its terminating positions.

With a switch stand constructed as described above, when the switch is trailed the weakest connection in the train of mechanism will break, and therefore the fracture will occur in the lug 14 engaged between the ears 15. After the lug 14 is broken the shaft 7 and remainder of the mechanism is free to operate, therefore no damage is done the vital and more expensive mechanism, and since the collar 12 is provided with a second lug it is only necessary to remove the collar from the shaft 7 and replace it in the reverse position so that the unbroken lug 95 will be inserted between the ears 15 to again place the switch stand in operative position.

It will be readily apparent that a particular advantage is obtained by locating the collar 12 on the shaft 7, since when the lug 14 is broken upon the trailing of the switch the operating shaft 7, target shaft 3, crank 10, etc., are all free to move with the switch. Therefore the target will not be falsified, but on the contrary will show the true position of the switch to succeeding traffic.

Referring particularly to Figs. 3 and 4 the invention is applied to the connection between the crank arm 10^a and the target shaft 3^a journaled in the casing 2^a. The 5 crank arm 10^a is of the double end type and is mounted adjacent the lower end of the target shaft 3^a. A collar 12^a is secured on the free end of the target shaft 3^a by a pin 13^a. A pair of diametrically opposite 10 comparatively thin lugs 14^a project from the periphery of the collar 12^a, either of which may be inserted between a pair of ears 15^a on the crank arm 10^a according to the position of the collar relative to the ears. The 15 ears 15^a are of materially greater thickness and strength than the lugs 14^a and are so spaced that they will snugly engage the lugs 14^a.

It will be readily apparent that when one 20 of the lugs 14^a is engaged between the ears 15^a the arm 10^a will have a positive engagement with the shaft 3^a.

The remainder of the switch stand is of 25 ordinary and well known construction as shown in Figs. 1 and 2, with the exception of the hand operating lever which will be secured directly to the operating shaft in the usual manner. Therefore this well known 30 construction will not be further illustrated or described.

The operation of this switch stand is substantially the same as that of Figs. 1 and 2. That is, if the switch be trailed the lug 14^a, which is inserted between the ears 15^a on the 35 arm will be broken, thus allowing the crank arm to rotate freely on the shaft 3^a and prevent the straining or damaging of any of the more essential and expensive parts. The collar 12^a is adapted to be removed from 40 the shaft 3^a and reversed in position when one of the lugs 14^a become broken and reversed in position so that the other lug is engaged between the ears 15^a, thus restoring the switch to operative condition.

45 Various modifications in the design and combination of parts may be made without departing from the spirit of my invention as defined in the appended claims. Therefore, I do not wish to be limited to the exact 50 construction illustrated in the accompanying drawings.

I claim:

55 1. In a switch stand a revoluble shaft, an arm loosely mounted on said shaft, a pair of ears on said arm, and a collar secured on said shaft, at least one lug projecting from said collar, said lug being inserted between said pair of ears on said arm, said lug being adapted to break to allow the free 60 operation of said switch stand when the switch is accidentally trailed.

65 2. In a switch stand a revoluble shaft, an arm loosely mounted on said shaft, a pair of ears on said arm, and a collar secured on said shaft, a pair of spaced lugs on said

70 collar, one of said lugs being inserted between said pair of ears on said arm, said lugs being of less strength than said ears and being adapted to break to allow the free operation of said switch stand when the switch is accidentally trailed, and said collar being adapted to be reversed on said shaft when one of said lugs is broken to allow the insertion of the other lug between the ears on said arm. 75

3. A switch stand having a vertical target shaft, an operating shaft operatively connected to said target shaft, an operating lever mounted to freely rotate on said operating shaft, a crank arm secured to the lower end of said target shaft and adapted to be connected to the switch rod, and means positively connecting said operating lever to said operating shaft, said means being weakened at its point of connection with 85 said lever so that it will break when the switch is trailed.

4. A switch stand having a vertical target shaft, an operating shaft operatively connected to said target shaft, an operating 90 lever mounted to freely rotate on said operating shaft, a crank arm secured to the lower end of said target shaft and adapted to be connected to the switch rod, a pair of ears projecting from said lever, a collar 95 secured on said operating shaft, at least one lug projecting from said collar and inserted between said ears on said operating lever to operatively connect said lever to said operating shaft, said lug being of less strength 100 than any other connection between the switch rod and operating lever so that it will break when the switch is trailed.

5. A switch stand having a vertical target shaft, a horizontal operating shaft operatively connected to said target shaft, a weighted operating lever mounted to freely 105 rotate on said shaft, a crank arm secured to the lower end of said target shaft and adapted to be connected to the switch rod, a 110 collar secured against rotation on said operating shaft, a pair of ears on said operating lever, a pair of spaced lugs projecting from said collar, one of said lugs being inserted between said pair of ears on 115 said lever to operatively connect said lever to said shaft, said lugs being of less strength than said ears and being adapted to break to allow the free operation of said switch stand when the switch is accidentally trailed, 120 and said collar being adapted to be reversed on said shaft when one of said lugs is broken to allow the insertion of the other lug between the ears on said lever.

6. A switch stand having a vertical target shaft, a horizontal operating shaft operatively connected to said target shaft, a weighted operating lever mounted to freely 125 rotate on said shaft, a crank arm secured to the lower end of said target shaft and adapt- 130

ed to be connected to the switch rod, a collar secured against rotation on said operating shaft, a pair of ears adjacent the end of said operating lever connected to said shaft, 5 a lug projecting from the periphery of said collar, said lug being inserted between said ears on said lever to operatively connect said lever to said shaft, said lugs being of less

strength than said ears and being adapted to break to allow the free operation of said 10 switch stand when the switch is accidentally trialed.

In testimony whereof I have hereunto set my hand.

WILLIAM MILTON BROWN.
